(57) **CLAIM**

The ornamental design for a trolling motor mount, as shown and described.

DESCRIPTION

FIG. 1 is a perspective view in an open position;

FIG. 2 is a right side view in an open position;

FIG. 3 is a left side view in an open position;

FIG. 4 is a front view in an open position;

FIG. 5 is a rear view in an open position;

FIG. 6 is a top view in an open position;

FIG. 7 is a bottom plan view in an open position;

FIG. 8 is a perspective view in a closed position;

FIG. 9 is a right side view in a closed position;

FIG. 10 is a left side view in a closed position;

FIG. 11 is a front view in a closed position;

FIG. 12 is a rear view in a closed position;

FIG. 13 is a top view in a closed position; and,

FIG. 14 is a bottom view in a closed position.

The broken lines illustrate environmental structure of the trolling motor mount, which forms no part of the claimed design.
